United States Patent Office

Des. 206,338

Patented Nov. 29, 1966

206,338

FOOD PAN

Myron M. Levin, Lincolnwood, and Norton R. Sachnow, Wilmette, Ill. (both of 4315 N. Lincoln Ave., Chicago, Ill. 60618)

Filed Aug. 16, 1966, Ser. No. 3,492

Term of patent 14 years

(Cl. D44—1)

FIG. 2 is a bottom view of the pan;

FIG. 3 is a front view of the pan;

FIG. 4 is a back view of the pan; and

FIG. 5 is a side view of the pan.

We claim:

The ornamental design for a food pan, substantially as shown.
